UNITED STATES PATENT OFFICE.

EZEKIEL H. HAWORTH, OF COUNCIL BLUFFS, IOWA, ASSIGNOR TO JAMES PATTERSON, HENRY COFFEEN, AND MARION SWALLOW, TRUSTEES, OF SAME PLACE.

DESIGN FOR A BADGE OR SEAL.

SPECIFICATION forming part of Design No. 21,267, dated December 29, 1891.

Application filed November 30, 1891. Serial No. 413,603. Term of patent 14 years.

To all whom it may concern:

Be it known that I, EZEKIEL H. HAWORTH, a male citizen of the United States of America, residing at Council Bluffs, in the county of Pottawattamie and State of Iowa, have invented and produced a new and original Design for a Seal, Badge, Emblem, and Design of The Commercial Pilgrims of America, a fraternal and social order; and I do declare the following to be a full, clear, and exact description of the same, reference being had to the accompanying drawing and description, forming a part thereof.

The drawing is an elevation showing a globe, of which the half containing the North and South American continents is visible.

The leading feature of my design is a hemisphere or half-globe showing the North and South American continents and surrounded by a circular space within an outer circle or

line of demarcation. In this space is placed over the north pole the picture of a crown. On the northern continent is shown the position of the Mississippi and Missouri rivers, with a dot on the latter, and to the left thereof, in the Pacific Ocean, is represented the grip, staff, and hat of a pilgrim. Also, just below these and bearing a little to the left of them is made a rectangular figure.

Having thus described all that is necessary to the understanding of my design, what I claim is—

The design for a seal or badge, as herein described and shown.

In testimony whereof I affix my signature in presence of two witnesses.

EZEKIEL H. HAWORTH.
